UNITED STATES PATENT OFFICE

ALBERT W. BANTON, OF EAST CHICAGO, INDIANA, ASSIGNOR TO O. F. JORDAN COMPANY, OF EAST CHICAGO, INDIANA, A CORPORATION OF INDIANA

RAILROAD SPREADER

Application filed September 29, 1930. Serial No. 485,048.

This invention relates to improvements in railroad spreaders and it consists of the matters hereinafter described and more particularly pointed out in the appended claims.

5 The invention is of especial advantage in railroad spreaders which embody a main spreader wing and a secondary wing or bank sloper, operatively connected to the outer end of the main spreader wing and the primary object of said invention is to provide 10 an improved brace connection between the outer end of the secondary wing or sloper and the car, whereby said secondary wing may be positively held in the desired operative position.

15 Another object of the invention is to improve the construction of the secondary wing or sloper brace which though quite heavy and strong in structure to withstand the great 20 strains imposed upon it in use, may be easily disconnected therefrom and readily placed in a carrying position on the car of the spreader when the same is to be moved in transport from one place of use to another.

25 The above mentioned objects of the invention together with others, as well as the many advantages thereof, will more fully appear as I proceed with my specification.

In the drawings:—

30 Fig. 1 is a view in side elevation of that portion of a railroad spreader intermediate its ends, embodying my invention.

Fig. 2 is a fragmentary perspective view of the main wing and secondary wing or bank sloper, together with associated parts of a 35 railroad spreader embodying my invention.

Fig. 3 is a longitudinal vertical sectional view on an enlarged scale through the inner top or end portion of the secondary wing or 40 sloper brace operatively connected to the wing post.

Fig. 4 is a longitudinal vertical sectional view on the scale of Fig. 3 of the outer bottom or end portion of the sloper brace.

45 Fig. 5 is a transverse detail sectional view through the sloper brace as taken on the line 5—5 of Fig. 4.

In general my improved railroad spreader includes a main spreader wing, so connected 50 to its associated wing post on the car as to

be not only positioned at the desired elevation but also at the desired angle with respect to the car. On the post is mounted a boom and between said boom and main wing is a power cylinder whereby the wing may be swung 55 about a horizontal axis into the desired position. Associated with the outer end of the wing so as to be capable of being swung about both a horizontal and a vertical axis is a secondary wing or bank sloper which may be 60 folded up against the wing for transport purpose or may be swung so as to shape or form the slope of a bank.

On the top end of the post is a bracket to which the inner end of a telescopic power actuated brace is connected, the other end of the brace being detachably connected to the other end of the secondary wing or sloper to hold it in operative position for bank sloping during spreading operations. This brace is quite 65 heavy and when the spreader car is to be transported from one place of use to another, said brace is first disconnected from the secondary wing or sloper and then engaged with other parts of the car for carrying purposes.

When said brace is thus being carried, the outer end thereof in its contracted position rests in a hook provided therefor on the cylinder between the boom and spreader wing.

On the outer end of the extensible part or plunger of the brace is a sheave, about which a chain that is fixed at one end with respect to the boom may be trained, after which the other end of the chain may be removably attached to the other or cylinder member of 80 said brace. When the outer end of the extensible part or plunger of the brace is disconnected from the sloper, and it is desired to dispose the brace in its out of the way position, for carrying, it is only necessary to extend said plunger. This acts to reduce the effective length of that part of the chain between the sheave and that end fixed with respect to the boom with the result that said 85 brace swings upwardly into a position adjacent the supporting hook into which it may be moved laterally. The brace may be secured to the supporting hook by a second chain provided therefor so that it cannot be 90 95 100

dislodged therefrom when the car is in transport.

Referring now in detail to that embodiment of the invention illustrated in the accompanying drawings:—1 indicates as a whole the car of a railroad spreader having front and rear wheeled trucks 2 and 3 for travel upon the rails 4 of a railroad track. At each side of the car, to the rear of the front trucks is an upright wing post 5 upon which a tube 6 is capable of both a turning and longitudinal movement. On the bottom end of this tube is secured a laterally extending hinge plate 7 to which the main spreader wing 8 is pivoted as at 9 to swing about a horizontal axis. On each tube 6 is mounted a lever arm 10 operatively engaged at its other end by the piston of an associated power actuating cylinder 11 mounted on the car forward of the post 5. This arm has a spline connection with the tube which is vertically movable with respect thereto whereby no matter what the relative position of the tube may have on the post, it may be turned thereon to swing 25 the wing toward and away from the car, into and out of its operative and inoperative positions.

12 indicates as a whole a boom that is associated with the main wing. This boom includes a horizontal arm 13 fixed at one end to the top of the tube 6 and an inclined strut 14 fixed at its bottom end to the top of the hinge plate 7. The other end of said arm and strut are connected together by a gusset 15. Pivoted to the gusset as at 16 is a power cylinder 17 that includes a yoke and guide tube extension 18. In the cylinder 17 is a piston, the associated rod of which extends down through the tube to engage with a bracket 19 on the top edge of the main spreader wing. This power cylinder is preferably pneumatically actuated from both ends so that the main spreader wing may be swung about its pivot 9 with the hinge plate 7 into the desired angular position.

Associated with the outer end of the main spreader wing is a secondary or "sloper" 20 as it is sometimes termed. This sloper has a pivotal connection 21 at its inner end with a hinge leaf 22 that is in turn pivoted at its bottom end as at 23 to the outer bottom corner of the main spreader wing. Said hinge leaf is formed at its top end to extend under an arcuate flange 24 on the front side of the main wing and this flange is concentric with the pivotal axis 23. On the other end of the secondary wing sloper is provided spaced ears 25 to receive a pin 26 whereby the outer end of the associated brace may be detachably connected thereto as will later appear. From the above, it is apparent, that the sloper may be swung into the desired angular position with respect to the main wing.

When the spreader as a whole is in transport from one place of use to another, the

sloper is folded flat (about the pivot 21) against the main wing and may then be swung about the pivot 23 into the inoperative out-of-the-way position as best shown in Fig. 1. To impart this last mentioned movement of the wing, I mount on the top edge of the main spreader wing between the post 5 and the bracket 19, a double acting power cylinder 27. Associated with said cylinder is a piston and piston rod 28 that is connected at its outer end to a runner block 29 having guided movement on a rail 30 on the top edge of the main wing. Pivoted at its inner end to the runner 29 is a rod 31, the outer end of which is detachably connected to the rear side of the sloper so that when the sloper is disposed in the plane of the main spreader wing it may be readily swung about the pivot 23 before mentioned.

The sloper 20 is swung into operative position about the pivot 21 by means of a pneumatically actuated, telescopic brace 32 which has a universal connection at both ends with the rear side of the sloper and with the car as indicated at 33, only the last mentioned connection being shown herein.

When the sloper is in operative position as shown in Fig. 2, wherein it is shaping or sloping a bank or is operating as a gathering wing, it stands at an angle to the plane of the spreader wing and to hold it in the desired position I provide a brace indicated as a whole as at 34 and which brace is a power actuated telescopic one.

On the top end of the wing post tube is mounted a laterally extending bracket 35 from which depends a boss 36. The brace 34 is operatively connected to the boss 36 with a somewhat loose fit or play and is adapted for detachable connection at its other end with the sloper by means of the spaced ears and pin 25—26 before mentioned. When disconnected from the sloper and the spreader car is transported from one place of use to another, said brace is adapted to be engaged in a supporting hook 37 depending from the cylinder 17 as best shown in Fig. 1.

The brace 34 comprises a relatively long cylinder 38 closed at one end by a head 39 that includes an eye 40 for the loose fit or play with the boss 36, this play or fit permitting an easy turning of the eye on said boss as well as a limited rocking movement. The other end of said cylinder is connected to one end of an extension tube 41 by means of a flanged fitting 42 and to the other end of said extension tube is secured a block 43. Within the cylinder 38 is a piston 44 having a piston rod 45 slidable through a stuffing boss 46 in the flanged fitting 42 as best shown in Fig. 3.

The extension tube 41 is of a cylindrical cross section while the guide block 43 is of a

rectangular cross section. Slidable through said block for projection from and retraction into the extension tube 41 is a plunger or brace tube 44^a, which is also of a rectangular cross section to prevent its turning in the block 43. To the outer extremity of said plunger or brace tube is secured a clevis like member 46^a and on the top side of said tube spaced from said extremity is a sheave 47. Pivoted to the clevis member 46^a as at 47^a, is a bracket 48 of a length to engage between the ears 25 on the secondary wing and when said bracket is so engaged, the pin 26 may be inserted through said ears and bracket to pivotally and detachably connect them together.

In the other end of the plunger or brace tube is secured a bearing block 50 through which the piston rod 45 extends, the extremity of said rod being secured in a cross head block 51, in turn secured to the corresponding end of the plunger or brace tube by a cross pin 52. On the top surface of the brace tube is secured a reinforcing strip 53 having holes 54 therein which register with similar holes in said tube.

The guide block 43 includes a pedestal 55 upon which is mounted a cylinder 56 with its axis arranged at a right angle to that of the plunger or brace tube 44^a. In this cylinder is located a piston 57 the associated rod or stem 58 of which extends through the guide block to pass through the desired hole 54 in the plunger or brace tube 44^a and its reinforcing strip 53. In this respect, it is pointed out that this tube and strip also have registering holes 54^a so arranged that when the plunger or brace tube has been retracted to its fullest extent, the stem 58 registers and extends through the same to lock said tube in this retracted position as best shown in Fig. 4.

In the cylinder 56 between its head and said piston is located a spring 59 that normally acts to project the piston and rod into locking engagement with the plunger or brace tube. A conduit 60 opens into the opposite or inner end of the cylinder whereby a pressure fluid may enter the same to move this piston against the action of the spring 59 to withdraw and hold the stem 58 out of locking engagement with the plunger or brace tube. Said conduit leads to a position on the spreader, convenient for the operator whereby the action of said stem may be controlled. Associated with each end of the cylinder 38 is a pressure fluid conduit 61 and 62 for the actuation of the piston 44 and its rod 45 in the desired direction, the inlet and outlet of fluid through said conduits also being controlled from the car of the spreader.

When fluid under pressure is admitted to one end or the other of the cylinder 38 by means of said conduits 61-62 it is apparent that the piston therein moves in one direction

or the other and a like movement is imparted through the rod 45 to the plunger or brace tube so that the same may be projected or retracted at will or held at any point between the limits of such movement.

It is apparent that when the bracket 48 is connected to the ears 25 on the secondary wing or sloper and the same is in operation, either to shape a bank or to carry material along to make a fill, a great strain is imposed upon the brace, which acts to extend the same. To amply resist this strain the brace as a whole must be exceedingly strong and to get the proper strength, it must be made quite heavy, too heavy in fact for convenient handling by manual labor. I provide in connection with said brace, means whereby the extending of the brace when disconnected from the sloper, assists in lifting the same into a position closely adjacent its supporting hook into which it may be easily moved or pushed laterally.

Such means includes a flexible member 63 in the form of a chain which is secured at one end to an arm 64 on the cylinder 17 and which may be trained about the sheave 47 on the plunger or brace tube 44^a to be detachably connected at its other end as at 65 preferably to a point on the pedestal 55 of the guide block 43.

After the spreading and bank sloping operation has been carried out and it is desired to transport the car to another place of operation, the bracket 48 is disconnected from the ears 25 of the sloper and the main wing 8 is then swung in toward the car. The chain 63 which when not in use hangs looped about the hook 37 as shown in Fig. 2, is then trained about the sheave 47 after which its free end is then attached to the pedestal 55, the plunger having been first retracted into the extension tube. Thereafter the plunger is projected from said tube thus shortening the distance between the sheave 47 and arm 64. As this distance is thus shortened, the sheave will travel up that end of the chain 63 until the extension tube 44^a reaches the plane of the hook 37 after which it may be pushed laterally thereinto. When so positioned in the supporting hook, a chain 67 which is secured at one end to the cylinder is wrapped or looped about the extension tube to secure the same in said hook. To prevent the plunger from being projected too far out of the extension tube, I provide a safety chain, 66 connected at one end to the guide block and at the other end to the plunger tube. After the brace has been thus positioned in the supporting hook 37 the sloper is swung into a position parallel with the main spreader wing when the rod 31 is connected to the rear side thereof. The cylinder 27 is then actuated to swing the sloper into the position shown in Fig. 1, and the car is ready for transport purpose.

When the new place of use has been

120

125

130

reached, the chain 67 is removed to release the brace, air is slowly admitted into the inner end of the cylinder so that the plunger is slowly projected. This operates to lift the brace upwardly a short distance and it is then manually swung laterally away from its supporting hook. Thereafter by gradually releasing the air, the brace lowers itself by gravity into a position wherein after the spreader wing and sloper have been repositioned the bracket 48 is again connected to the ears 25 by the pin 26.

The end of the chain 63 may be then detached from the pedestal and removed or de-
15 trained from about the sheave and is looped about the supporting hook as before.

From the above, it is apparent that the brace which is a heavy power operated one, may by the use of the chain as described, raise and lower itself into and out of substantially operative position, with respect to its supporting hook so far as heavy manual lifting is concerned. Thus the heavy brace may be readily and quickly manipulated.

25 While in describing the invention, I have referred in detail to the form, arrangement and construction of the various parts thereof, the same is to be considered as illustrative only so that I do not wish to be limited there-
30 to except as may be specifically set forth in the appended claims.

I claim as my invention:—

1. A railroad spreader embodying therein a car, a post at one side of the car, a main spreader wing operatively mounted on the post, a telescopic brace connecting the post and wing and actuating the latter, a second wing pivotally mounted at one end on said main wing for a swinging movement into and out of bank shaping or sloping position with respect thereto and means independent of said telescopic brace for operatively connecting the other end of said second wing with said post.

45 2. A railroad spreader embodying therein in a car, a post at one side of the car, a main spreader wing operatively mounted on the post, a telescopic brace connecting said post and wing and actuating the latter, a second wing pivotally mounted at one end on said main wing for a swinging movement into and out of bank shaping or sloping position with respect thereto and means independent of telescopic brace for operatively and detachably connecting the other end of said second wing with said post.

50 3. A railroad spreader embodying therein a car, a post at one side of the car, a main spreader wing operatively mounted on the post, a second wing pivotally mounted at one end on said main wing for a swinging movement into and out of bank shaping or sloping position with respect thereto and a telescopic brace connecting the outer end of the secondary wing with said post.

4. A railroad spreader embodying therein in a car, a post at one side of the car, a main spreader wing operatively mounted on the post, a second wing pivotally mounted at one end on said main wing for a swinging movement into and out of bank shaping or sloping position with respect thereto, a brace member operatively connected at one end to said post and a second brace member telescopic with respect to the first brace member and operatively connected at its other end to the outer end of the secondary wing.

5. A railroad spreader embodying therein in a car, a post at one side of the car, a main spreader wing operatively mounted on the post, a second wing pivotally mounted at one end on said main wing for a swinging movement into and out of bank shaping or sloping position with respect thereto, a brace member operatively connected at one end to said post, a second brace member telescopic with respect to the first brace member and operatively connected at its other end to the outer end of the secondary wing and means for locking the members of the brace together in the desired operative relation.

6. A railroad spreader embodying therein a car, a post at one side of the car, a main wing connected at one end to said post, means including a brace connected to said post and another part of the main wing for supporting the same, a secondary wing, a brace detachably connected the post and secondary wing and means associated with the first brace for supporting the secondary wing brace at a point spaced from the post when said last mentioned brace is detached from said secondary wing.

7. A railroad spreader embodying therein a car, a post at one side of the car, a main wing connected at one end to said post, means including a brace connected to said post and another part of the main wing for supporting the same, a secondary wing, a telescopic brace having one part connected to the post and an extensible part detachably connected to the outer end of the secondary wing, and means on said first mentioned brace adapted for engagement by one of said parts of the telescopic brace for supporting the same after said extensible part has been disconnected from said secondary wing.

8. A railroad spreader embodying therein a car, a post at one side of the car, a main wing connected at one end to said post, means including a brace connected to said post and another part of the main wing for supporting the same, a secondary wing, a brace detachably connecting the post and secondary wing and means associated with the first brace for supporting the secondary wing brace in substantially the plane of the main wing when said last mentioned brace is detached from said secondary wing.

9. A railroad spreader embodying therein

a car, a post at one side of the car, a main spreader wing operatively connected to said post, a secondary wing, a brace including an extensible part adapted for detachable connection with said secondary wing, means adapted for attachment to the extensible part of the brace and operable in the extension of said part when detached from the secondary wing to lift the brace and means for supporting said brace from the car when so lifted.

10. A railroad spreader embodying therein in a car, a post at one side of the car, a main spreader wing and a lifting brace therefor connected to said post, a secondary wing connected at one end to the main wing, a brace including a part connected to the post and an extensible part adapted for detachable connection with the other end of the secondary wing, means connected at one end to the main wing brace and adapted for detachable connection with the extensible part of the second mentioned brace and operable upon extension of said part when detached from the secondary wing to lift the same upwardly 25 and means on the main wing brace to support said secondary wing brace when thus lifted.

11. A railroad spreader embodying therein in a car, a main spreader wing operatively connected thereto, a second wing pivotally connected to the main wing for movement into and out of operative position with respect thereto, a telescopic brace operatively connected at one end to the car and including a projectable part adapted for detachable connection with said second wing, a support on the car for a part of said brace, and means secured at one end to said car and adapted for detachable connection at its other end 40 with said projectable part and operable in the projection thereof to cause the brace to swing into the plane of its support.

In testimony whereof, I have hereunto set my hand, this 19th day of September, 1930.

45 ALBERT W. BANTON.
